UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

BINDING-POST FOR ELECTRICAL CONDUCTORS.

1,154,583.

Specification of Letters Patent.

Patented Sept. 21, 1915.

Application filed February 24, 1913. Serial No. 750,258.

To all whom it may concern:

Be it known that I, CHARLES J. KLEIN, a citizen of the United States, residing at Milwaukee, in the county of Milwaukee and 5 State of Wisconsin, have invented new and useful Improvements in Binding-Posts for Electrical Conductors, of which the following is a full, clear, concise, and exact description, reference being had to the accompanying drawing, forming a part of this 10 specification.

My invention relates to binding posts for electric conductors.

It has among its objects to provide an improved binding post adapted to hold a conductor securely in position.

A further object of my invention is to provide an improved binding post which is adapted to establish an intimate electrical 20 contact with the conductor.

Other objects and advantages of my improvement will hereinafter appear.

In order that my invention may be fully and clearly disclosed I have illustrated one 25 embodiment of the same in the accompanying drawings.

Figure 1 is a top plan view of the binding post with the conductor in position therein. Fig. 2 is a transverse sectional view of the 30 same. Fig. 3 is a transverse sectional view of the binding post with the conductor clamped therein.

The binding post illustrated when broadly considered comprises a shallow flexible cap 35 or cup 1 and means for compressing the same upon a conductor. This cap 1 is preferably formed of soft metal and provided in its top with a central opening 2 to receive a binding screw 3. It is further provided with a side wall 4 extending about three-quarters of 40 the way around the same, whose rim is adapted to engage with the surface of a support 5 in which the screw 3 is threaded. A portion of this wall and preferably a portion 45 of the top of the cap is cut away as shown at 6 to provide an entry for the conductor 7.

When it is desired to attach the conductor 7 to the binding post it is only necessary to 50 insert the end of the same in the opening 6

so that it extends into the chamber formed between the walls of the flange 4 and the periphery of the screw 3. The screw 3 is then rotated to cause its head to depress the material of the cap as shown in Fig. 3. When 55 this is done the conductor is clamped securely between the cap 1 and the base or plate 5 so that it cannot be accidentally disengaged therefrom and the conducting parts are brought into such intimate mechanical 60 engagement as to insure a good contact. The security of the fastening means is further enhanced by the fact that the conductor if desired may extend practically entirely through the channel formed between the cap 65 wall and the screw. However, it is not essential that the conductor extend entirely around the screw, as even if the conductor is only inserted a short way in the chamber the clamping action is very efficient. Obviously, 70 however, for mechanical reasons, the passage of the conductor around the shank of the screw serves to produce a more secure connection.

What I claim as new and desire to secure 75 by Letters Patent is:

1. The combination with a screw binding post, of an inverted cup-shaped washer centrally penetrated thereby, said washer being of soft metal and yieldable centrally under 80 the pressure of said screw to be thereby shaped to and clamped against an inclosed conductor terminal.

2. The combination with a screw binding post, of a clamping washer centrally penetrated thereby, said washer having a depending peripheral flange and a flat soft metal top, the central portion of said top being 85 compressible by said screw to clamp a conductor against said peripheral flange and to 90 be itself clamped between such conductor and said screw.

3. The combination with a screw binding post, of a soft metal clamping washer centrally penetrated thereby, said washer being 95 peripherally supported and centrally unsupported to yield centrally downward and peripherally outward under pressure of said screw for thereby shaping to and closely clamping upon a conductor coiled therein. 100

4. The combination with a screw binding post, of a soft metal clamping washer centrally penetrated thereby, said washer having a depending peripheral flange and being yieldable to the pressure of said screw to spread and in spreading to shape about and firmly clamp the conductor to be secured.

In witness whereof, I have hereunto subscribed my name in the presence of two witnesses.

CHARLES J. KLEIN.
